[57] CLAIM

The ornamental design of a razor dispenser, as shown and described.

DESCRIPTION

FIG. 1 is an enlarged perspective view of a razor dispenser showing my new design;

FIG. 2 is top plan view thereof;

FIG. 3 is a bottom plan view thereof;

FIG. 4 is a front elevational view thereof;

FIG. 5 is an elevational view taken from the left of FIG. 2;

FIG. 6 is a rear elevational view thereof; and

FIG. 7 is an elevational view taken from the right of FIG. 2 with a portion broken away to show razors which are illustrated in broken lines for illustrative purposes only.

FIG. 1***FIG. 2******FIG. 3***

FIG. 4***FIG. 5******FIG. 6******FIG. 7***
